UNITED STATES PATENT OFFICE.

FRANCIS J. BULLIVANT, OF ST. LOUIS, MISSOURI, ASSIGNOR TO VALLEY ELECTRIC COMPANY, OF ST. LOUIS, MISSOURI, A CORPORATION OF DELAWARE.

SHORT-CIRCUITING DEVICE FOR ELECTRIC MOTORS.

Application filed February 18, 1924. Serial No. 693,519.

This invention relates to electric motors, and more particularly to mechanism for short circuiting the rotor winding, such as is used more particularly in motors of the single phase type.

One of the objects of this invention is to improve the construction of such a short circuiting device so as to facilitate the operation thereof and render a lighter construction possible.

Another object is to provide an improved construction for such a device which will be compact so as to occupy small space.

Another object is to provide an improved construction which will be cheap to manufacture and reliable in operation.

Further objects will appear from the detail description taken in connection with the accompanying drawing, in which:

Figure 1 is a side view, partly in section, of a motor embodying this invention;

Figure 2 is a front end view of the centrifugal elements, and

Figure 3 is a perspective view of the mechanism.

Referring to the accompanying drawing, 1 designates the stator of usual construction provided with bearings 2 carrying the shaft 3 of the armature or rotor 4. Mounted on the front of the armature is a commutator hub 5 carrying a commutator 6 constructed of a plurality of insulated segments in the usual manner and connected to the rotor winding 7 of any desired type. In the present instance the commutator 6 is of the so-called radial type in which the brushes 8 bear yieldingly upon a radial face 9 of the commutator segments. The parts so far enumerated may be of any usual well known construction and will, therefore, require no further description.

The commutator 6 is provided with an internal bore 10 exposing the edges of the commutator segments. This bore 10 is of uniform diameter with the bore 11 of the commutator hub 5. Mounted for sliding movement on the shaft 3 and within the bore 10-11 is a support or carrier 12. This support is adapted to fit loosely within the bore 10-11 so as to leave ample clearance therearound. The carrier 12 is further provided with an external annular groove or recess 13 adapted to receive a series of contacting elements 14. The elements 14 may each be provided with one or more perforations 15

through which a wire or other flexible connecting element may be passed so as to secure the elements 14 together. The elements 14 are ordinarily formed by punching from sheet metal, usually copper, and a considerable number of them are strung upon a wire or similar means passed through the perforations 15 so as to form a string or so-called "necklace" of contacting elements. This string is then laid about the support 12 and within the groove 13 before inserting the support in the bore 10-11. The support 12 may be provided with ears 16 to which are pivoted a pair of links or tension members 17 pivoted at their other ends to a pair of centrifugal elements 18. The elements 18 are of special form so as to surround the shaft 3 and are pivoted thereto at 19. The pivot 19 is placed on the shaft somewhat forwardly of the commutator 6 and on the elements 18 forwardly of their center of gravity so that when these elements move under the influence of centrifugal force, the bodies thereof will swing forwardly about the pivot 19. Surrounding the shaft 3 and between the centrifugal elements 18 and the hub of the support 12 is a coiled spring 20 bearing at one end against the hub of the support 12 and at the other against a washer or collar 21 surrounding the shaft 3 and restrained from movement thereon by a pin 22. The spring 20 thus provides a yielding abutment against which the support 12 bears. The spring 20 also urges said support rearwardly when the rotor is at rest. Rearward movement of the support 12 will spring the centrifugal elements 18 rearwardly and together against or close to the shaft 3, and at the same time will carry the contacting elements 14 rearwardly so as to be out of contact with the segments of the commutator 6.

The operation of this device is as follows: When the rotor is at rest, the spring 20 urges the support 12 to the rear carrying the elements 14 out of contact with the commutator segments and collapsing the centrifugal elements 18. When the motor starts up and gathers a speed, a point will be reached where the centrifugal force acting on the elements 18 and tending to move it outwardly and forwardly will be sufficient to draw the support 12 forwardly by means of tension members 17 with sufficient force to overcome the pressure of the spring 20. The strength of the spring 20 may be adjusted so that this

force takes place at a predetermined speed. As soon as this speed is passed, the centrifugal action of the elements 18 will operate to slide the support 12 forwardly so as to carry 5 the contacting elements 14 into contact with the inner edges of the commutator segments as indicated by the dotted line position shown in Figure 1. When in this position the elements 14 are adapted to form a series 10 of bridges connecting the individual commutator segments with the hub 5 so as to short circuit the commutator. The rapid rotation of the rotor tends to throw the elements 14 outwardly with considerable force 15 so that a firm contact is made both with the commutator segments and with the hub 5. There is thus provided an effective short circuit for the commutator.

It will, therefore, be seen that this invention accomplishes its objects. A structure is provided in which the centrifugal elements being pivoted forwardly of their centers of gravity will upon movement under the influence of centrifugal force swing forwardly. This structure further provides that these centrifugal elements may be mounted at the forward end of the rotor which arrangement is adapted to improve the compactness of the mechanism and to 30 save space, since the centrifugal elements are mounted adjacent the rest of the short circuiting mechanism and the connections therebetween are short so that space otherwise wasted may be utilized. A further saving of space is attained at the rear end of 35 the rotor at which point the centrifugal elements have heretofore been placed.

In accordance with the present invention no moving mechanism is mounted at the rear 40 of the rotor so that the space occupied thereby is thus saved. The direct connection between the centrifugal elements and the other moving parts also tends to reduce frictional resistance and thus render the operation of the device more reliable while at 45 the same time making it possible to reduce the size and cost of the various elements and thus cheapen the manufacture.

It is obvious that various changes may be 50 made in details of construction without departing from the spirit of this invention; it is, therefore, to be understood that this invention is not to be limited to the specific details shown and described.

Having thus described the invention, what is claimed is:

1. In an alternating current motor having a commutator at the front end thereof, means for short circuiting the commutator comprising, a series of short-circuiting elements adapted for movement forwardly to contact with the commutator, a support for said contact elements, and centrifugal elements pivoted forwardly of the commutator and connected to move said support forwardly to contacting position. 60 65

2. In an alternating current motor having a commutator at the front end thereof, means for short circuiting the commutator comprising, a series of short-circuiting elements adapted for movement forwardly to contact with the commutator, a support for said contact elements, and centrifugal elements pivoted forwardly of said support and connected to move said support forwardly to contacting position. 70 75

3. In an alternating current motor having a commutator at the front end thereof, means for short circuiting the commutator comprising, a series of short-circuiting elements adapted for movement forwardly to contact with the commutator, a support for said contact elements, centrifugal elements pivoted forwardly of the commutator, and tension members connected to said centrifugal elements and adapted to move said support. 80 85

4. In an alternating current motor having a commutator at the front end thereof, means for short circuiting the commutator comprising, a series of short-circuiting elements adapted for movement forwardly to contact with the commutator, a sliding support for said contact elements, centrifugal elements pivoted forwardly of said support on said shaft, and links connected with said centrifugal elements and adapted to slide said support forwardly to contacting position. 90 95

5. In an alternating current motor having a commutator at the front end thereof, means for short circuiting the commutator comprising, a series of short-circuiting elements adapted for movement forwardly to contact with the commutator, a sliding support for said contact elements, centrifugal elements pivoted forwardly of said support on said shaft, links connecting said centrifugal elements with said support, and a yielding abutment between said support and said centrifugal elements. 100 105

In testimony whereof I affix my signature this 22nd day of January, 1924.

FRANCIS J. BULLIVANT.
